UNITED STATES PATENT OFFICE.

CHARLES R. GIBBS AND EDWARD FEDDON, OF HARRISONBURG, VIRGINIA.

CRIMPING-BOARD FOR BOOTS AND SHOES.

SPECIFICATION forming part of Letters Patent No. 240,996, dated May 3, 1881.

Application filed November 5, 1880. (No model.)

To all whom it may concern:

Be it known that we, CHARLES R. GIBBS and EDWARD FEDDON, of Harrisonburg, in the county of Rockingham and State of Virginia, have invented a new and useful Improvement in Crimping-Boards for Boots and Shoes, of which the following is a specification.

The invention relates to an improvement in crimping-boards for boots and shoes, as hereinafter described, and particularly pointed out in the claim.

The object of the invention is to produce a crimping-board which, while subserving the purposes of the crimping-board now in use, will also impart to the leather the form of the foot, whereby, when the upper of the boot or shoe is removed from the board, it may be at once placed upon the last and the shoe or boot completed without again stretching and working the leather, as has been necessary heretofore in the manufacture of shoes and boots.

Heretofore crimping-boards have been constructed with flat sides, and the upper edge of the foot portion has been even and plain. They have not had the spring and concave to form the instep and top of the foot, or the configuration to give the upper the right and left shape. Upon these crimping-boards the wetted leather was stretched by pinchers and by rubbing and clamped or tacked on the edges, to remain until dry. The operation of stretching and working the leather on the board required a great deal of time and labor, and after being dried the leather was removed and placed upon the last, where it was again stretched and worked to give it the contour of the foot—viz., the right and left and instep formation. The leather was thus necessarily submitted to two operations of rubbing and stretching, which not only consumed labor and time, but also had the effect of weakening the leather and producing thereby an inferior shoe.

Our crimping-board, constructed, as aforesaid, to not only crimp the upper, but to give it the right and left and instep formations, dispenses with the latter operation above described, and saves thereby the injurious effect upon the leather caused by the second soaking, rubbing, stretching, &c., as well as the time and labor employed in said operation, and produces a much better shoe or boot at a reduced cost. We place the wetted leather upon the crimping-board, and at one operation of stretching

the upper is made to conform to the foot, when 55 it is placed upon the last and the shoe finished at once. The last is used not as a stretcher, but simply as a convenient block to hold the various parts of the shoe in proper relation while they are being put together. The boot 60 or shoe thus made is produced at a considerably reduced expense, and is a very superior article.

The construction of the crimping-board is represented in the accompanying drawings, in 65 which—

Figure 1 represents a perspective view with the upper and front of the leg portion in position and crimped. Fig. 2 represents views of the crimping-board and the crimped upper 70 and front of the leg portion, and Fig. 3 a bottom view.

The letter A indicates the vertical body portion, which is shaped along its length to crimp the leg of the boot, and is formed on its 75 front edge with the curved portion B, for crimping or forming the instep to the leather, and with a longitudinal foot portion, C, having the opposite sides curved, as at D and E, for causing the upper to partake of the right and 80 left sides of the foot.

Heretofore lasts for boots and shoes have been formed with curves which impart the right and left formations to the upper; but such is not our invention, and is therefore not 85 claimed.

In our invention the upper and leg portion, after being subjected to the action of the crimping-board, are placed upon the ordinary last and finished as usual.

What we claim as our invention, and desire to secure by Letters Patent, is—

The crimping-board herein described, consisting of the vertical body portion A, formed integral with the foot portion C, having the 95 side curves, D and E, to impart the right and left formation of the foot to the leather, and with the curve B, for imparting the instep formation to the same, all as herein described.

In testimony that we claim the foregoing 100 improvement in crimping-boards for boots and shoes, as above described, we have hereunto set our hands this 17th day of September, 1880.

CHARLES R. GIBBS.
EDWARD FEDDON.
